WALL FORM

Matthew A. Jorsch, Detroit, Mich.

Application March 22, 1939, Serial No. 263,467

15 Claims.

(Cl. 25—131)

This invention relates to forms for concrete walls and particularly to sheet metal wall forms.

An object of the invention is to provide a form for a concrete wall minimizing the embedding of tie or spacer members in the formed wall.

Another object is to provide a concrete wall form comprising spaced panels held upright and in proper opposed relation by stanchions engaging or definitely spaced from the outer faces of such panels.

Other objects are to mount said stanchions on elongated forms for a wall footing, to adapt such footing forms to definitely anchor the stanchions in proper positions, to adapt the stanchions to interconnect aligned units of the footing forms in abutting relation, and to provide simple devices for quickly securing the panels to or releasing them from the stanchions.

A further object is to provide an improved means for forming window or other openings in a monolithic concrete wall, and to provide an adjustment for such means adapting it to various widths of openings.

A further object is to connect stanchions at opposite sides of the wall by suitable tie members, and to adapt the latter to various spaced relations of the stanchions.

A further object is to provide a concrete wall form having a provision for forming a wall with a ledge for seating floor joists or a facing of brick or the like, or for reducing a wall thickness at a certain level for any desired purpose.

These and various other objects are attained by the construction hereinafter described and illustrated in the accompanying drawings, where-in:

Fig. 1 is an isometric view of a portion of the form as assembled to form the footing and lower part of a wall.

Fig. 2 is a cross-sectional view of said portion of the form, showing a concrete filling therein.

Fig. 3 is a fragmentary isometric view showing the relation of a spacer bar to one of a pair of stanchions, surmounted by such bar.

Fig. 4 is an isometric view of a spacer plate adapted to underlie the entire form.

Fig. 5 is a fragmentary side elevation of the foot portion of one of said stanchions, showing its relation to a pair of abutting footing form units which jointly carry such stanchion.

Fig. 6 is a cross sectional view taken on the line 6—6 of Fig. 5, showing particularly the interlocking relation of the stanchion and the abutting footing form units.

Fig. 7 is an isometric view of an extensible

unit adapted to be interposed between the spaced panels of the form to produce the lower portion of a window or other opening.

Fig. 8 is cross sectional view of said unit, showing how it is supported by the wall-forming panels.

Fig. 9 is a perspective view of a latch plate employed to secure most of the panel plates to the stanchions.

Fig. 10 is a perspective view of an elongated type of latch plate used to secure the upper plates of the outer wall panel and offset-forming plate of either panel to the stanchions.

Fig. 11 is a perspective view of a spring clamp used at various points to hold together parts of the form.

Fig. 12 is a fragmentary top plan view of two outer footing form units as they intersect at a wall corner, showing a fitting for interlocking such units and closing the end opening of one thereof.

Fig. 13 is a perspective view of said fitting.

Fig. 14 is a fragmentary top plan view showing two inner footing form units intersecting at a wall corner and a fitting for interlocking the same.

Fig. 15 is a perspective view of said fitting.

Fig. 16 is a fragmentary top plan view of a floor of a building, showing the form arranged to extend a wall upwardly from a margin of such floor.

Fig. 17 is a fragmentary interior view of such wall and form, sectionally showing the floor.

Fig. 18 is an exterior view of such wall and form.

Fig. 19 is a perspective view of a panel-supporting wire bracket.

Fig. 20 is a vertical sectional view, taken on the line 20—20 of Fig. 18, showing said bracket in use.

In these views, the reference characters A and B designate spaced inner and outer wall-forming panels, each comprising a plurality of similar rectangular panel plates 1, abutting each other end to end, and superposed one on another to establish a desired length and height for the panels. Welded or otherwise rigidly secured to the exterior face of each panel plate is an angle bar reinforcement 2, bordering and substantially flush with the periphery of the plate. Also rigidly carried by each plate 1 on its exterior face is a pair of horizontally elongated U-shaped reinforcing bars 3 spaced from each other and from the top and bottom edges of the plate.

The panels A and B are held upright and in

definite spaced relation by stanchions 4 disposed in exterior proximity thereto, and seating at their lower ends on inner and outer horizontally elongated sheet metal footing forms 5, which also carry the panels. Such forms are suitably spaced apart, each comprising a suitable number of units arranged in end-to-end relation, two thereof being shown in Fig. 1. Each footing form unit comprises a vertical web member 6, a coextensive shelf member 7 inwardly projecting from the member 6 at the top of the latter, and a trough-shaped member 8 substantially coextensive with the member 6 and exteriorly extending along the base thereof. Each shelf member 7 is formed at its inner edge with an upturned flange 1a, against which the superposed panel plate 1 abuts, said flange assuring a proper spacing and parallelism of the lower panel plates, provided that the footing forms are parallel. At the ends of each units, flanges 9 project above the ends of the trough member 8, converging toward each other.

Sheet metal spacer plates 10 are employed to establish and maintain the proper relation of the inner and outer footing forms 5, said plates extending transversely beneath and forming supports for such forms. Such plates are reinforced at their longitudinal margins by upturned flanges 11 and their ends are similarly reinforced by flanges 12. As best appears in Fig. 4, the flanges 11 are terminally spaced from the flanges 12 forming gaps 13 into which the trough members 8 of the footing forms may fit to properly space the inner and outer forms. The end portions of each spacer plate rigidly carry a pair of upstanding sheet metal channels 14 which fit beneath and support the shelf members 7 of the footing forms, as Fig. 2 discloses. Said spacer plates are preferably located at the junctures of the footing form units, as per Fig. 1.

The stanchions 4 each comprise a pair of opposed channel-shaped sills 15, and a series of vertically spaced connections 16 between such sills, said connections being each reinforced by an upturned inner marginal flange 17 and a downturned outer flange 18. Further connections between said sills are formed by a cap piece 19 at the top of each stanchion and an extension 20 carried by the base portion of each stanchion upon its outer face, such extension projecting exteriorly adjacent to the web 6 of the form underlying the stanchion and fitting into the trough member 8 of such form to resist such outward thrust as is exerted on the stanchion in use. Each extension 20 is preferably centrally upwardly slotted from its lower edge, as indicated at 21, so that in locating the stanchions at the junctures of aligned footing form units, the slits 21 may engage abutting, divergent flanges 9 of the units, so that the stanchions interconnect the units in their abutting relation and are anchored in place by said flanges. (See Figs. 5 and 6.)

It is often desirable to reduce the width of a concrete wall at a certain height, an objective of such a reduction frequently being the formation of a ledge to seat joists or a facing tier of brick or other units. The present invention effects a reduction of wall width, with resultant formation of a ledge, by offsetting one of the panels A and B toward the other at the desired height, the offset being formed by a course of relatively narrow horizontally disposed panel plates 22, the outer edges of which surmount a course of the panel plates 1 and the inner margins of which carry the upward continuation of the offset panel. The

plates 22 are reinforced by up-standing flanges 23 set back from the longitudinal edges of such plates and serving also to properly position the plates 1 adjacent to the inner margins of the plates 22. To hold the plates 22 rigidly in place on the underlying course of panel plates, there is employed a plurality of approximately U-shaped spring clamps 24 formed preferably of sheet metal, said clamps embracing the lapped outer margins of the members 22 and top flanges of the plates 1. Such clamps are also preferably used at various other points to assure firm engagement, as for example to embrace the abutting flanges of adjoined panel plates. (See Fig. 1.)

The panel plates which lie against the stanchions are firmly secured to the latter by small sheet metal latch plates 25 which are centrally upwardly slotted as indicated at 26 and thus adapted to straddle abutting flanges of the channel bars 3 and connections 16. Elongated sheet metal latch plates 27 each having two upwardly extending slots 28 interconnect the outer stanchions with those panel plates 1 which are inwardly spaced from said stanchions, said plates having each of their end portions formed with one of the slots 28, the inner slots receiving channel flanges on the panel plates and the outer slots receiving flanges 17 of connections 16. Similar latch plates preferably releasably connect the horizontal plates 22 to the stanchions, as appears in Fig. 1.

Inner and outer stanchions 4 are oppositely disposed and connected at their upper ends by spacer bars 29 formed preferably of two spaced elongated angle bars rigidly connected at their ends by similar angle bars. The elongated angle bars have vertical flanges adapted to straddle the stanchions and horizontal flanges which seat on the caps 19 of the stanchions. Pins 30 are transversely mounted in the end portions of said bars to engage the outer faces of the connected stanchions, and latch elements 31, formed of heavy wire, have terminal eyelets which slip over the pins 30 to pivot said elements, the other ends of the latter being hooked to engage inner edges of the stanchion sills. Preferably a plurality of apertures 32 are formed in the end portions of the bars 29 to permit such adjustment of the pins 30 as will accommodate them to various spaced relations of inner and outer stanchions. Spacing of the latter is determined by the thickness of the wall to be formed. In addition to exercise of their spacer function, the bars 29 may serve to carry a plank runway (not shown) for wheelbarrows employed in delivering cement to the wall form.

In producing window or other openings, in use of the described form, a pair of angle brackets comprising vertical plates 33 and horizontal plates 34, carried at the lower ends of the vertical plates, are mounted between the panels A and B in a spaced relation determined by the desired width of opening. The plates 33 are reinforced at their upper margins by flanges 35 having terminal extensions beyond said plates to seat on the top edges of a course of the plates 1. The opposed faces of the plates 33 and top faces of the plates 34 are reinforced by flanges 36. Connecting the plates 34 is an extensible member comprising a pair of overlapping plates 37 to vary the joint length thereof. The member comprised by the plates 37 is bolted to and between the plates 34, as indicated at 41.

At the corners of a wall to be formed, one of the relatively transverse outer footing form units

5 overlaps and closes the end of the other, and has its own end closed by a sheet metal fitting 42 which further serves to interlock the two units. The fitting 42 is bent to form end portions 43 and 44 which fit into the troughs 8 of the two footing units and is slotted upwardly as indicated at 45 to accommodate the flanges 9 of said units. At its upper margin, the fitting is formed with a reinforcing flange 46. (See Figs. 12 and 13.)

Inner footing form units in meeting at a wall corner are interlocked, as shown in Fig. 14, by a sheet metal fitting 47 of box shape. Said fitting fits into the trough portions 8 of the meeting units and is upwardly slit as indicated at 48 to straddle the abutting flanges 9 of the units. The slit 48 is formed at one of the vertical edges of said fitting, which has its diagonally opposite edge portion split from top to bottom to form portions to fit within troughs 8. The upper end 20 of the fitting is partially closed for reinforcing purposes as indicated at 49.

Figs. 16, 17 and 18 show the form as extended up from any floor 50 of a building. In such floor, holes 51 suited to accommodate the stanchion extensions 20 are either formed during pouring of the floor or after the same has hardened. Stanchions 4, as hereinbefore described, are anchored in these holes, serving to hold in place the inner panel B, seating upon and rising from said floor. The outer panel A is held in place by a suitable number of stanchions 4 which are seated upon beams 4a, similar in all respects to the stanchions 4 but disposed horizontally adjacent to the outer face of the wall 52 which underlies the floor 50, and is to be now upwardly extended. The beams 4a are arranged with their ends formed by the extensions 20 bearing against said wall, as best appears in Fig. 16, the other ends of such beams overlapping the extensions 20 of aligned adjoining beams 4a. Thus the extensions 20 on the beams so space the beams outwardly from the wall as to form an elongated space suited to accommodate the extensions 20 of the stanchions seating on said beams. To hold the beams 4a in place, bolts 53 engaging said beams, are extended through the wall 52, and preferably through window or door openings 54 in such wall, to engage anchorage bars 55 engaging the inner face of such wall. Thus the panels A and B may be erected on successively higher floors of a building to permit extending the latter to any desired height. After thus forming a wall rising from any floor, as 50, the holes 51 of such floor may be readily eliminated by filling the same with concrete.

When it is desired to support a panel without using either the footing forms or the floors as a support, there is employed a suitable number of such brackets 56 as are shown in Figs. 19 and 20. Each of these brackets comprises a length of wire bent to U-shape, and further bent at its closed end so that, in resting on one of the connectors 16, it may be hooked to engage beneath the flange 18 of said connector, while its parallel ends seat on and project beyond the flange 17. Thus said projecting ends may serve as a panel support as clearly appears in Fig. 20. This is particularly useful in extending the outer panel upwardly above any floor of a building, 70 as in Fig. 18.

The described form may be quickly set up or taken down and is of such durable construction that it may be used a great many times without material deterioration. Since the plates 5 are 75

the only elements of the form to become permanently embedded in the concrete wall, these are the only parts requiring replacement after each use of the form.

5 The invention is presented as including all such modifications and changes as come within the scope of the following claims.

What I claim is:

1. A wall form comprising a pair of spaced 10 footing forms having shelf portions projecting toward each other, stanchions seated on such shelf portions, two substantially parallel spaced panels, respectively seated on the shelf portions of the respective footing forms, means detachably securing the panels to the stanchions, and tie members connecting the footing members and comprising elements underlying and seating said shelf portions.

2. In a wall form, a footing form comprising elongated units adjoined in end-to-end relation, a panel seating on said footing form to define one side of a wall, and stanchions seating on the footing form and holding said panel in place, said stanchions being disposed at the junctures of said units, and elements on the ends of said units engageable by the stanchions upon a downward sealing movement of the stanchions, whereby the seated ends of stanchions establish an interlock between the adjoined ends of the units.

3. In a wall form, the combination with a stanchion, of a panel comprising a substantially vertical plate seating against said stanchion, a substantially horizontal plate seated at a margin 35 thereof on said vertical plate and extending from the stanchion, a second vertical plate seating on said horizontal plate at a margin thereof opposed to said margin, means for latching each of said plates to the stanchion, and a reinforcement on said horizontal plate upwardly projecting and elongated in substantial parallelism with said margins of such plate, and definitely spacing the seated edge of the second vertical plate from the stanchion.

4. In a wall form, the combination with a pair of spaced panels defining a wall, of a pair of spaced window-forming members, adapted to fit between said panels, the upper ends of said members being formed with reinforcing flanges projecting above and seating on the panels and thus suspending said members, and a window-forming member of variable length, connecting the lower ends of the first-mentioned window-forming members.

5. In a wall form, the combination with two transversely adjoined horizontally elongated footing forms each comprising a vertical web and a shelf member projecting from the top of said web, and the webs being formed with adjacent flanges at the adjoined ends of said forms, of a sheet metal member slotted to straddle said flanges and thereby interlock said forms in their adjoined relation.

6. A wall form as set forth in claim 5, said sheet metal forming an end closure for one of said footing forms.

7. A wall form comprising a pair of horizontally elongated, oppositely spaced footing forms, each having a substantially vertical web to define an outer face of a wall footing, and a shelf member inwardly projecting from the upper portion of the web to define a top face of said footing, stanchions seating on said shelf members, tie members underlying and interconnecting the footing forms, a pair of substantially

parallel spaced panels seated in opposed relation on the shelf members between the stanchions and restrained by the stanchions from separative movement, and means on the footing forms restraining the seated ends of the stanchions from separative movement.

8. In a wall form as set forth in claim 7, means underlying the shelf members for transmitting load therefrom to said tie members.

9. A wall form comprising a pair of horizontally elongated oppositely spaced footing forms, each having a substantially vertical web, a trough-shaped member exteriorly projecting from the base of said web, and a shelf member inwardly projecting from the top of the web and serving to define a top face of a wall footing, stanchions seating on said shelf members and having offset downward extensions engaged in said trough-shaped members, tie members interconnecting said footing forms, and a pair of substantially parallel spaced panels seated in opposed relation on the shelf members and restrained from separative movement by the stanchions.

10. A wall form as set forth in claim 9, said shelf members having upturned inner margins and the panels being confined between such margins and the stanchions.

11. In a wall form, a footing form comprising elongated units adjoined in end-to-end relation, each having a substantially vertical web to define the outer face of a wall footing, a shelf member projecting from the top portion of said web to define a top face of said footing, and a trough member outwardly projecting from the lower portion of the web, stanchions seating on the shelf members, each having a laterally offset downward extension, engaged in one of said trough members to resist lateral shifting of the stanchion, and elements on the adjoined ends of said units engaged by said extension to interlock said units.

12. In a wall form, the combination with a pair of spaced wall-defining panels, of a pair of substantially opposite stanchions disposed in exterior proximity to the panels and resisting separative movement of the panels, a spacer member superposed on the stanchions and downwardly flanged to hold it in place on the stanchions, and means for latching the spacer member to the stanchions in selective spaced relations of the stanchions.
13. In a wall form, the combination with a stanchion and an elongated substantially horizontal spacer member superposed on the stanchion, of a pin mounted in said spacer member at one side of the stanchion, and a latch member pivoted on said pin and hooked to detachably engage the stanchion at its other side.
14. In a wall form, a pair of spaced, horizontally elongated, substantially parallel footing forms, comprising substantially vertical web members to define the outer faces of a wall footing and shelf members projecting toward each other to define top faces of said footing, and a tie member underlying said footing forms having upward projections resisting separative movement of the footing forms, and having a provision for resisting movement of such forms toward each other, and having upstanding elements between the web members providing seats for said shelf members.
15. In a wall form, a footing form comprising elongated units adjoined in end-to-end relation, a panel seating on said footing form to define one side of a wall, and stanchions seating on the footing form and holding said panel in place, said stanchions being disposed at the junctures of said units and establishing an interlock between the adjoined ends of the units, the units having projections at their adjoined ends and the stanchions having their lower portions slotted to straddle the adjoined projections.

MATTHEW A. JORSCH.
